PLASTIC EGG CARTONS

David C. Trimble, Yorklyn, Del., assignor, by mesne assignments, to Hercules Incorporated, New Castle County, Del., a corporation of Delaware

Filed Apr. 8, 1966, Ser. No. 541,200

3 Claims. (Cl. 229—2.5)

The present invention relates to an egg carton, and has for an object to provide means in an egg carton for resisting twisting or warping of the carton about its longitudinal center line, as when the loaded carton is lifted by one corner thereof. Further objects of this invention are to provide such a means which can be formed integrally in the carton and is therefore inexpensive, and which is sufficiently strong and durable so that it will function dependably and efficiently throughout the useful life of the carton.

While the present invention is useful in egg cartons of other materials, it has been designed primarily for use with an egg carton such as that which forms the subject matter of my co-pending United States patent application Ser. No. 541,188, filed Apr. 8, 1966, that is, an egg carton molded from a sheet of foamed or expanded plastic material. In particular, the present invention is designed for use with an egg carton having a base member that is divided by partitions into a plurality of egg-receiving pockets, and also having a pair of cover members each of which is adapted to cover a portion of the base member and is hinged to the base member along one of the longitudinal side edges thereof so that it can be swung inwardly, together with slotted posts for receiving an edge portion of each cover member to position and frictionally to grip the same, thereby holding the cover members in closed position. The objects of the invention have been attained by the use of notches in the cover members, which notches extend out of the plane of the side wall of the cover member and are adapted to engage against the posts to prevent sliding of the cover member relative to the posts. A further advantage derived from this invention is that the notches, by forming the same to open on the top of the cover members, may serve as thumb holes to facilitate opening the carton.

With the above and other objects in view, a presently preferred embodiment of the invention is hereinafter described with reference to the accompanying drawings in which:

FIG. 1 is a perspective view of an egg carton embodying the present invention with one of the cover members illustrated in phantom in the open position and partly broken away.

FIG. 2 is a fragmentary view in top plan of the egg carton of FIG. 1.

FIG. 3 is a fragmentary transverse sectional view taken substantially on the line 3—3 of FIG. 2.

FIG. 4 is a fragmentary longitudinal sectional view taken substantially on the line 4—4 of FIG. 2 and illustrating the carton with the cover thereof in closed position.

FIG. 5 is a fragmentary transverse sectional view similar to FIG. 3 but on an enlarged scale and with the cover members closed.

With reference to the drawings, the present invention is illustrated as embodied in an egg carton thermoformed from a sheet of any suitable foamed plastic material, such as polystyrene, polyethylene, polypropylene, copolymers of ethylene and propylene and the like, or alternatively, formed from other materials such as pulp. The illustrated carton comprises a tray-like base member 1 and a pair of generally U-shaped cover members 2, each of which is hinged along one edge to an upper longitudinal edge of the base member 1 by a hinge 3 and is adapted to be

2

swung between a closed position overlying the base member and an open position in which the open top of the base member is exposed. With a carton of foamed plastic material, the hinge 3 may be of the type and may be formed in the manner disclosed and claimed in my co-pending United States patent application Ser. No. 541,189, filed Apr. 8, 1966.

The base member 1 includes a pair of opposed side walls 4 and a pair of opposed end walls 5, which are discontinuous as noted below and which are tapered outwardly or diverge in the direction away from the bottom plane 6 of the base member at angles of approximately sixty degrees to the plane 6. The walls 4 and 5 also have the upper edges thereof disposed in and thereby define a top plane 7 that is substantially parallel to the bottom plane 6.

The illustrated carton is of the standard 2 x 6 type in which there are one dozen egg-receiving pockets 9 arranged in two rows of six pockets each. The means for dividing the base member 1 to provide the pockets 9 comprises a longitudinal partition 10 and five transverse partitions 11, which intersect the side walls 4 and end walls 5, thereby rendering the same discontinuous. The partitions 10 and 11 are inverted V-shaped with upper edges 12 and 13, respectively, and side walls 14 and 15 that, like the side walls 4 and end walls 5 of the base member 1, are inclined at angles of about sixty degrees to the bottom plane 6 of the carton. The pockets 9 are thus each defined by four opposed side walls, i.e., the side walls 4, the side walls 14 of the partition 10 and a pair of the side walls 14 of the partitions 11, except for the end pockets wherein the end wall 5 is used in lieu of one of the walls 14, all of which walls diverge upwardly from a substantially square bottom wall 16 disposed in the bottom plane 6 and which may be cushioned.

At the intersection of the longitudinal partition 10 with each of the transverse partitions 11, there is provided a post which is either a flat-topped, cover-supporting post 17 or a slotted cover-retaining post 18, there being in the illustrated embodiment of the invention an arrangement such as is disclosed and claimed in my co-pending United States patent application Ser. No. 541,187, filed Apr. 8, 1966, that is, an alternating arrangement of five posts 17 and 18 consisting of three cover-retaining posts 18 located on each at the center and the two outer positions and two cover-supporting posts 17 located one each at the two intermediate positions. Each of the posts 17 has a flat top 19 and depending walls 20. The tops 19 are in the top plane 7 of the base member 1 and are substantially square with the corners thereof centered over the upper edges 12 and 13 of the partitions 10 and 11. The cover-retaining posts 18 have walls 21 that are also arranged in a pattern that is substantially square in transverse cross-section with the corners thereof disposed directly over the upper edges 12 and 13 of the partitions 10 and 11. The posts 18 rise above the top plane 7 of the base member 1 and are provided with slots 22 that extend inwardly from the upper or free end thereof to a point at least level with but preferably slightly below the top plane 7 of the base member 1, the slots 22 being arranged longitudinally of the base member 1 and from corner-to-corner of the posts 18 or, in other words, with the center line thereof in a plane that is normal to the top plane 7 and includes the upper edge 12 of the longitudinal partition 10. The posts 18 also include tops 23 that slope inwardly and downwardly toward the slots 22 from the outermost corners thereof for the purpose of directing the edges of the cover members 2 into the slots 22.

The walls 20 and 21, as well as corresponding walls 24 and 25 that are formed respectively between the walls 4 and 15 and between the walls 5 and the adjacent walls 4 and 14, serve as corner walls for the pockets 9 and act to

confine the eggs more closely in the pockets and to provide resilience so that the walls 4, 5, 14 and 15 can be flexed outwardly to accommodate eggs of a size larger than that for which the pockets were primarily dimensioned and thus providing a single carton that is sufficiently versatile that it can be used with a number of different sizes of eggs. The corner walls 20, 21, 24 and 25 may be planar or may be slightly convex and are arranged at an angle of substantially seventy-five degrees to the bottom plane 6 of the base member 1.

The cover members 2 are each generally U-shaped in transverse cross-sections and include a top wall 26 and a depending skirt portion including an inclined side wall 27, which is inclined relative to the top wall 26, a normal side wall 28, that is normal relative to the top wall 26 and end walls 29 extending between the two side walls. The cover members 2 are formed integrally with the base member 1 and are hinged along the edge of the inclined side wall 27 to the upper or free edge of the side wall 4 by means of the hinge 3.

The cover members 2 are dimensioned such that when they are closed, the normal side walls 28 are substantially normal to the top plane 7 of the base members 1 with the outer surfaces of the two cover members substantially in contact or in surface-to-surface abutting relation to each other and the top walls 26 are substantially in spaced parallel relation to the plane 7. The closed position of the cover members 2 is as illustrated in FIG. 5, that is, with the edge portions of the side walls 28 inserted in the slots 22 of the posts 18 and the free edges thereof seated on the tops 19 of the posts 17. At the same time, the thickness of that portion of each of the walls 28 that is received within the slots 22 is more than one-half the width of the slots 22 so that the combined thickness of the wall portions is greater than the width of the slot, thus requiring that they be forced into the slots and insuring that they will be frictionally retained therein.

For a more detailed description of the specific configuration and dimensions of the base member 1 and the cover members 2, and of the functions and advantages thereof, reference is made to my above noted co-pending application Ser. No. 541,188. Formed in the wall 28 of each of the cover members 2 is a pair of notches 30, each of which is substantially semi-conical with the base thereof at the top wall 26 of the cover member and the apex thereof adjacent to the free edge of the wall 28. The notches 30 are designed to receive the thumbs of the user to facilitate opening the cover members 2, which, of course, would otherwise be quite difficult in view of the fact that the side walls 28 of the cover member 2 are in abutting relation and afford no opening or hand-hold by means of which the user can easily grasp the cover members 2 to open the same. In the illustrated embodiment, the notches 30 in each of the cover members are opposed so that the total thumb hole is substantially conical.

The notches 30 also are designed to add stiffness to the carton and to prevent twisting or warping thereof, as for example, when the loaded carton is lifted by one corner. For this reason, the notches 30 are disposed longitudinally of the wall 28 on opposite sides of and substantially in engagement with one or more of the posts 18, more particularly, in the illustrated embodiment, the notches 30 are located inwardly of the two posts 18 at the opposite ends of the base member 1. Thus, the one notch 30 of each wall 28 at the one end of the carton

will, through engagement with the post 18, prevent sliding of that wall 28 in the one direction relative the post 18 and the notch 30 at the other end of the carton will similarly prevent sliding of the wall 28 in the other direction.

What I claim and desire to protect by Letters Patent is:

1. An egg carton comprising a tray-like base member with an open top in a top plane and having longitudinal side walls and a plurality of partitions dividing the same into a plurality of egg-receiving pockets arranged in two rows longitudinally of the base member, a plurality of posts disposed along the longitudinal center line of the base member and extending above the top plane of said base member, said posts having slots arranged longitudinally of the base member and extending inwardly from the free edges thereof through that portion of said posts disposed above the top plane, and a pair of complementary cover members each of which includes a flat top wall that is disposed substantially in spaced parallel relation to the top plane of the base member when said cover members are closed and overlies substantially one-half of said base member, and substantially planar side walls with substantially straight free edges depending from the longitudinal edges of said top wall, each of said cover members being hinged to said base member along the free edge of one of said side walls and having the other of said side walls disposed in surface-to-surface abutting relation with the corresponding side wall of the other cover member and provided with edge portions that are adapted to be received within said slots when said cover members are closed, said other side wall of one of said cover members having portions displaced out of the plane of the side wall in the direction away from the abutting side wall to provide a plurality of notches with one notch in engagement with one of said posts on one side thereof longitudinally of the base member and another notch in engagement with one of said posts on the opposite side thereof longitudinally of the base member, whereby the engagement of said notches with said posts will prevent relative movement between the respective edge portions of said cover members longitudinally of the base member, said notches extending to the plane of the top wall to define thumb holes to facilitate opening of said cover members.
2. An egg carton in accordance with claim 1 in which said notches are substantially semi-conical with the base thereof in the plane of the top plate of the cover members, thereby providing thumb holes to facilitate opening of said cover members.

3. An egg carton in accordance with claim 1 in which said posts include two posts disposed adjacent to each end of the base member, and said notches include a notch formed in each cover member inwardly of each post to define an opposed pair of notches adapted to engage the inner edge of each post.
